WILLIAM HENRY MERRICK, OF PHILADELPHIA, PENNSYLVANIA.

Letters Patent No. 100,651, dated March 8, 1870.

IMPROVEMENT IN SAFETY-MECHANISM FOR HOISTING-APPARATUS.

The Schedule referred to in these Letters Patent and making part of the same

I, WILLIAM HENRY MERRICK, of Philadelphia, county of Philadelphia, State of Pennsylvania, have invented certain improved Safety-Mechanism for Hoisting-Apparatus, of which the following is a specification.

Nature and Object of the Invention.

My invention consists in the combination in hoisting-apparatus of an idler-pulley bearing on a driving-belt, with mechanism for applying a brake to the pulley or shaft driven by the belt, and for controlling the stopping, starting, and reversing-gear of the driving-engine, all substantially as described hereafter, so that if the belt accidentally breaks or slips from the pulleys, the engine will be stopped simultaneously with the application of the brake.

The figure in the accompanying drawing represents a side view of my improved safety-mechanism for hoisting-apparatus.

A represents a shaft, to be driven by an adjacent steam-engine, and on this shaft is a pulley, B, for receiving the driving-belt C, the latter passing around the larger pulley D, on a shaft, E, which is the medium, in combination with any suitable mechanism, for raising and lowering the hoisting-cage.

On the same shaft E, or on the pulley D, is a friction-pulley, F, to the periphery of which are adapted the blocks H of a brake-band I, the opposite ends of the latter being connected to a lever, J, one end of the band on one side, and the other end of the band on the other side of the fulcrum-pin m of the said lever, as shown in the drawing.

To this lever is connected the lower end of a rod, K, the upper end of which has an elongated eye or slot b, and through the latter passes a spindle, c, on which an idler-pulley, L, can revolve freely, the said spindle being secured to an arm, M, hung loosely to the driving-shaft A, or to any stationary object adjacent thereto, so that the said idler-pulley is free to bear with its own weight and that of its arm or arms on the driving-belt C.

A lever, N, is secured to a fulcrum-spindle, d, which is allowed to vibrate in any stationary object, the lever being connected by a rod, z, or otherwise, to the throttle-valve of the engine, and to the stopping, starting, and reversing-gear of the same, for it should be understood that the movement of the lever N must control that of the engine, the lever being operated, in the present instance, by a cord or rod, P, which may be so situated as to be grasped by any one occupying a position on the cage of the hoisting-apparatus.

The lever J is provided with a weight, Q, on each side of which a rod, f, is connected to the said lever, each rod having a vertically-elongated eye or slot, h, through which passes a pin, i, on the lever N.

It has not been deemed necessary to illustrate or describe the engine or its reversing-gear, as the engine may be of the ordinary construction, and any of the common devices for stopping, starting, and reversing the engine may be employed.

Operation.

In the drawing, the operating parts of the mechanism are shown in their normal condition, that is to say, in the position which they will assume when the engine has been stopped, the lever J being depressed and the brake-band L applied to the pulley F, the lever N being retained by the rods f f of the weighted lever J in the position which determines the stoppage of the engine.

We will suppose it to be necessary to hoist the cage, and that in order to effect this purpose it is necessary to elevate the controlling-rod P, on doing which the lever N will be so operated as to open the throttle-valve, thereby admitting steam to the cylinder of the engine, and at the same time so operating the reversing-gear that the pulley A will be driven, say, in the direction of the arrow, and the cage, consequently, hoisted. But, simultaneously with these movements, the said lever N, by acting on the rod f, elevates the lever J, thereby relieving the pulley F from the friction-band I; thus the hoisting-pulley D is released simultaneously with the starting of the engine in the desired direction for hoisting the cage.

When it is desired to stop the cage, the controlling-rope P is pulled down to its original position, thereby permitting the weight Q to depress the lever J and to apply the brake-band I simultaneously with the stoppage of the engine.

When the cage has to be lowered, the controlling-rope P is pulled down, thereby causing the lever N to start and reverse the engine, at the same time the pin i of the said lever, acting on the rod f, elevates the lever J, as before, and relieves the pulley F from its brake-band.

When the cage has been lowered to the desired point, the controlling-rope P is again elevated, so as to cause the lever N to assume its normal position, thereby stopping the engine, while the brake-band is applied as before.

Owing to the vertically-elongated eye in the rod K, the above-described movements of the lever J cannot disturb the idler-pulley L, which always performs its duty, that of maintaining the driving-belt tight, without disturbing the brake-lever J, but should the driving-belt be suddenly broken, or should it slip from the pulleys, the idler-pulley will be released, and will fall by its own weight and that of its arm M, and its spindle, striking the bottom of the eye in the rod K, will depress the brake-lever J, thereby applying the brake.

and at the same time restoring the lever N to its normal position.

I have referred to the above-described mechanism as applied to hoisting-apparatus for mines, but it will be evident that it may be applied to hoisting-mechanism for inclined planes, or in fact to any other hoisting-apparatus in which safety is desirable.

Different adaptations of the mechanism will, in many cases, involve the necessity of a different construction and arrangement of parts. For instance, it is not absolutely necessary that the controlling-rope P should be so arranged as to be within reach of those in the cage. In fact, the controlling-rope may, in some instances, be entirely dispensed with, and the lever M placed within the control of an operator stationed at a given point on an inclined plane.

Again, it is not absolutely necessary that the braking device illustrated and described should be employed

in all cases, as other braking-apparatus, equally effective, might be used.

Claim.

In hoisting-apparatus, the combination, substantially as described, of an idler-pulley, bearing on a driving-belt, with mechanism for applying a brake to the pulley or shaft driven by the belt, should the latter break, and for controlling the stopping, starting, and reversing-gear of the driving-engine, all substantially as set forth.

In testimony whereof I have signed my name to this specification in the presence of two subscribing witnesses.

WILLIAM HENRY MERRICK.
